(57) **CLAIM**
The ornamental design for a display screen with a transitional graphical user interface, as shown and described.

DESCRIPTION

FIG. 1 is the first image in a sequence for a display screen with a transitional graphical user interface showing our new design in accordance with a first embodiment;

FIG. 2 is a second image thereof;

FIG. 3 is a third image thereof;

FIG. 4 is a fourth image thereof; and,

FIG. 5 is an alternate fourth image in a sequence for the display screen with a transitional graphical user interface in accordance to the second embodiment, wherein the sequence of images consist of FIGS. 1, 2, 3, and 5.

The appearance of the images sequentially transitions between the images shown in FIGS. 1, 2, 3, and 4 in accordance with a first embodiment and between the images shown in FIGS. 1, 2, 3, and 5 in accordance with a second embodiment. The process or period in which on image transitions to another forms no part of the claimed design.

The broken lines shown in the drawings illustrate the display screen with a graphical user interface that forms no part of the claimed design. Additionally, the body of text and any other text illustrated in broken lines also forms no part of the claimed design. Furthermore, the intervening white space between solid-line borders and broken lines is not part of the claimed design. The unornamented surface bounded by the broken-line borders is not part of the claimed design. Unseen portions of the display screen form no part of the claimed design.
